[57] CLAIM

The ornamental design for combined portable heat insulated cooler and warmer, as shown and described.

DESCRIPTION

FIG. 1 is a perspective view of a combined portable heat insulated cooler and warmer showing my new design;
FIG. 2 is a front elevational view of FIG. 1;
FIG. 3 is a rear elevational view of FIG. 1;
FIG. 4 is a top plan view of FIG. 1;
FIG. 5 is a bottom plan view of FIG. 1;
FIG. 6 is a left side elevation view of FIG. 1;
FIG. 7 is a right side elevation view FIG. 1;
FIG. 8 is a perspective view of FIG. 1 in an open position;
FIG. 9 is a perspective view of an alternate embodiment of FIG. 1;
FIG. 10 is a top plan view of FIG. 9;
FIG. 11 is a front elevational view of FIG. 9;
FIG. 12 is a rear elevational view of FIG. 9;
FIG. 13 is a left side elevation view of FIG. 9; and,
FIG. 14 is a right side elevation view of FIG. 9.
The undisclosed bottom view of FIG. 9 is the same as FIG. 5.
